(No Model.)

J. H. PORTER.
SELF LEVELING BERTH.

No. 276,874.

Patented May 1, 1883.

UNITED STATES PATENT OFFICE.

JAMES H. PORTER, OF BOSTON, MASSACHUSETTS.

SELF-LEVELING BERTH.

SPECIFICATION forming part of Letters Patent No. 276,874, dated May 1, 1883.

Application filed July 15, 1882. (No model.)

To all whom it may concern:

Be it known that I, JAMES H. PORTER, of Boston, in the county of Suffolk and State of Massachusetts, have invented certain Improvements in Self-Leveling Berths, of which the following is a specification.

This invention relates to that class of self-leveling berths shown in Letters Patent of the United States granted to me May 3, 1881, No. 241,062, in which a beam pivoted centrally to a fixed support is employed, said beam having offset ends, to which the ends of the berth are attached, and being provided with friction-rollers around its pivot, to prevent the binding tendency of the offset berth.

The present invention has for its object to provide certain improvements in the means for pivoting the offset bar to its support, in the means for pivoting the ends of the berth to the bar, and in other details of construction, whereby space is economized, the automatic or self-leveling action of the berth is made more complete and satisfactory, and other useful results are produced.

To these ends my invention consists in the improvements which I will now proceed to describe and claim.

Of the accompanying drawings, forming a part of this specification, Figure 1 represents a front elevation of a self-leveling berth embodying my improvements. Fig. 2 represents a transverse section on line $x-x$, Fig. 1. Fig. 2^a represents a similar section with the berth in a different position. Fig. 3 represents a longitudinal section on line $y-y$, Fig. 2. Fig. 4 represents a modification. Fig. 5 represents a section on line $z-z$, Fig. 4.

The same letters of reference indicate the same parts in all the figures.

In the drawings, A represents the berth, and B the pivoted bar having offset ends, to which the berth is pivoted. In carrying out my invention I pivot the bar B to the state-room wall C, or other support, by means of a ring, D, rigidly attached to the bar, a concentric ring, E, rigidly attached to the wall and inclosing the ring D, and a series of interposed friction-balls, F, placed at suitable intervals in coinciding grooves formed in the proximate surfaces of the rings D E. Said rings may be of any desired diameter and thickness. I prefer

to make them of as large diameter as the length of the bar B will allow, and of as little thickness as possible. It will be observed that the ring D constitutes the journal of the bar B, and the fixed ring E the bearing for said journal. By thus constructing the journal and bearing I am enabled to make both much shorter—that is, having much less projection from the wall C—than the journal and bearing shown in my former patent, the increased diameter compensating for the decrease in length or outward projection. The bar B and the berth are therefore located much nearer the rear wall of the state-room than heretofore, and much saving in space is effected. The friction-balls projecting equally into both rings support the ring C and its attachments both vertically and laterally.

I do not limit myself to making the rings E continuous. If desired, they may be divided into short segments, two or more in number. The movable ring D may be upon the inner or outer side of the fixed ring or bearing E, as desired.

The offset ends of the bar B are formed into rings B', standing at right angles to the rings D E. The ends or heads of the berth A are composed of rings a, inclosed in the rings B', and concavo-convex plates a', of sheetmetal or other suitable thin material, attached to the rings a, and each having a radius equal to about half the length of the berth. The proximate surfaces of the rings B' and a are provided with coinciding grooves, in which are placed balls I, which permit the berth to rotate freely, as on a longitudinal axis. By making the ends of the beam to encircle the ends of the berth and giving the ends of the berth the concavo-convex form, with the radius shown, I am enabled to make the length of the berth exceed that of the bar, and thus obtain the maximum longitudinal capacity in a given space, the head and feet of the occupant being enabled to project through the bearing on which the berth is journaled and come in close proximity to the ends of the state-room. The described radius of the end plates enables them to be placed almost in contact with the ends of the state-room without colliding therewith when the berth rocks or pitches.

In case it is desired to furnish additional

support for the berth, the offset ends of the bar B may be connected by a beam, K, extending under the berth, lengthwise thereof, and provided with a curved surface, L, concentric with the pivot of the bar B. Under this curved surface is placed a reversely-curved track, M, also concentric with the pivot of the bar B. The surface L and track M are provided with coinciding grooves, in which are placed balls O.

It will be seen that all the friction-rollers employed are balls running in grooves. I find that balls are superior to all other forms of friction rollers, because the axis of motion in each ball will always be at right angles to the power or pressure exerted. Consequently operation of the balls will be the same under all possible motions of the vessel.

By my above-described improvements I am enabled to operate a berth athwartships quite as well as fore and aft. Said improvements are applicable to tables, chairs, settees, and other structures as well as to berths:

The support afforded for the ends of the berth by the rings B', formed on the bar B, enables the berth to be tipped to one side and secured in the position shown in Fig. 2^a, so as to serve as a sofa, the bar B being fastened when the berth is so used, if desired. The wall C, to which the ring E is attached, may be a section of wall or a back plate, which is detachably connected by bolts R R to a fixed wall or other support, so that by detaching the section C from its support the location of the berth may be readily changed. For example, the berth may be taken from a state-room to the cabin or deck. I prefer to provide the ends of the berth with curved rods or wires U to support a curtain, V, the curtain being adapted to be gathered at the rear edge of the berth when not in use, and to be drawn over upon the rods, so as to form an arched covering over the berth. The curtain moves with the berth and prevents the occupant of the berth from seeing external objects, and thus prevents a common cause of sea-sickness.

If desired, the ends of the berth may be made only partially circular, the upper portion being cut off or given any desired ornamental form.

Figs. 4 and 5 represent a modification in which the bar B is passed at its center through a disk, h, which has pivots b c projecting from its opposite sides into bearings b' c', formed in a fixed supporting-frame, d. The pivots b c present acute angles, or slightly-rounded acute

angles, to the bearings b' c', and are adapted to rock freely on said bearings. The pivot b is arranged above the bearing b', and the pivot c below the bearing c', as shown in Fig. 5. This arrangement enables the pivots and bearings to resist to the best advantage the side strain caused by the weight of the berth on the offset beam.

I claim—

1. The combination, with the offset bar and the berth or equivalent structure supported thereby, of the journal D, affixed to the bar, the fixed bearing E for said journal, and the interposed friction-rollers, said journal and bearing having enlarged diameters, and being short in outward projection or length, whereby the bar and berth or equivalent structure are brought close to the rear wall or support of the bar, as set forth.

2. The combination, with the offset bar and the berth or equivalent structure supported thereby, of the grooved ring or journal D, attached to the bar, the fixed grooved ring or bearing E, and the friction-balls located in the grooves between the proximate surfaces of the rings, whereby the ring D, bar B, and the berth are supported in all directions, as set forth.

3. The pivoted bar B, having its ends offset and formed into rings B', combined with the berth or equivalent structure, having the circular or partially circular ends projecting through and journaled in the rings B', as set forth.

4. The pivoted bar B, having its ends offset and formed into internally-grooved rings B', combined with the berth, having at its ends the externally-grooved rings a a, and the friction-balls I, interposed between said rings, as set forth.

5. The combination, with the pivoted bar B, having offset ends, and the berth or its equivalent pivoted thereto, of the beam K, connecting said offset ends under the berth, and provided with the curved surface L, the curved track M, supported under the surface L, and the interposed friction-balls, as set forth.

In testimony whereof I have signed my name to this specification, in the presence of two subscribing witnesses, this 8th day of July, 1882.

JAMES H. PORTER.
